ABSTRACT OF THE DISCLOSURE

Detergent mixtures consisting of: (a) an alkylsulfonic acid containing a sulfonic acid group per 7 carbon atoms at most, (b) a low-molecular oxalkylation product of a lower alkyl amine, and (c) a phosphate of alkanols of 4 to 8 carbon atoms are useful as surface active agents for alkaline baths.

This is a continuation-in-part of our copending application Ser. No. 701,119 filed Jan. 29, 1968, now abandoned.

The present invention relates to surface active agents especially to wetting agents for alkaline baths, in particular for mercerizing- and leaching baths.

The present wetting agents are mixtures containing:

- (a) alkyl sulfonic acids or their alkali metal salts having on an average one sulfonic acid group per 7 carbon atoms at most,
- (b) an amine of the formula

in which R is alkyl of 2 to 5 carbon atoms, n is 2 or 3 and m is a number of 1 to 2, which amines are in the following referred to as "alkyl dialkanol amines," and (c) a phosphoric acid ester of alkanols of 4 to 8 carbon atoms, and, if desired, further usual auxiliary agents.

It is already known from German Auslegeschrift No. 1,014,067 that higher molecular weight aliphatic sulfonic acids containing more than one sulfonic acid group per molecule are used as wetting agent for mercerizing- and leaching baths.

Furthermore, it is known from German Pat. No. 955,857 that mixtures of alkyl sulfonates of 5 to 10 carbon atoms in the alkyl radical and alkyl sulfates, the alkyl radical of which containing 10-16 carbon atoms can be used as wetting agents for mercerizing baths. Additionally, in order to improve the solubility of the sulfonates in the mercerizing liquors, small amounts of aliphatic alcohols, amines, alkylamines, ether alcohols or naphthene acids can be used as auxiliary solvent.

Moreover, it is known from German Pat. No. 719,432 to use a mixture of a sulfonic acid of an alkane having 5 to 7 carbon atoms and an amine having β -hydroxyethyl residues. These mixtures, however, are not satisfactory as to their wetting power and their tendency to foam.

It has been found that mixtures of: (a) aliphatic sulfonic acids containing on an average one sulfonic acid group per 7 carbon atoms or their alkali metal salts, (b) alkyl dialkanolamines, and (c) phosphoric acid esters of aliphatic alcohols of an average molecular weight, which may be partially saponified are used as extremely active and clearly soluble wetting agents even in cold alkaline baths.

2

It was surprising and unforeseeable that the addition of the alkyl dialkanolamines and of the phosphates to the mentioned alkyl sulfonic acids or their alkali metal salts leads to such active, clearly soluble and not-foaming wetting agents. The technical advantages of the wetting agent-mixtures according to the process of the present invention are, for example, to be seen from the tables shown further below. Especially advantageous in industrial use are the mixtures according to the present invention for obtaining highly improved shrinkage values. The fact, that the mercerizing baths are practically free of foam is especially advantageous when working on yarn mercerizing machines. To the mercerizing- or leaching baths prepared by using the mixtures of the present invention other surface active compounds or mercerizing agents can be added, if desired, such as ethylene oxide condensation products or cresols. If it is deemed desirable, other known auxiliaries, such as lower alcohols, can still be added.

As starting substance for the preparation of the alkyl sulfonic acids, containing per one sulfonic acid group at most 7 carbon atoms, saturated aliphatic hydrocarbons are appropriate, such as light petrol boiling at 30-80° C. or aliphatic and cycloaliphatic hydrocarbons of 10-20 carbon atoms, which may be branched. Especially advantageous are straightchained hydrocarbons of 10-20 carbon atoms, as obtained by molecular sieve separation processes. Molecular sieves are, for example, certain synthetic zeolites the crystal lattices of which having interspaces of definite dimensions which are accessible through pores of a certain width. These pores allow for example the inner adsorption of n-paraffins by excluding branched components. In a separate stage the n-paraffins are desorbed and gathered. The n-paraffins can also be separated by using the so-called urea-process.

The above-mentioned molecular-sieve-process is described for example in the publication of J. J. Griesmer, H. B. Rhodes and K. Kiyonaga, Erdoel und Kohle, Erdgas, Petrochemie, 13, (1960), page 650, in the publication of Ch. K. Hersh, "Molecular sieves," New York (1961) and in Ind. Engng. Chem., 54 (1962), No. 5, page 13 and Erdoel und Kohle, 12 (1959), page 406.

The urea-process is explained in a paper of E. Weintraub in Erdoel und Kohle, Erdgas, Petrochemie, 14 (1961), page 910.

According to the process of the present invention at least one sulfonic acid group is introduced into the lower hydrocarbons such as into light petrol, having an average molecular weight of about 60, and 2 sulfonic acid groups into the higher hydrocarbons such as into an n-paraffin of an average molecular weight of 215. The sulfonic acid alkali metal salts are prepared from these hydrocarbons advantageously by sulfo-chlorination according to the Reed-process and subsequent alkaline saponification but also the thiourea-process of Sprague and Johnson or the method of Johnson and Douglas as well as the oxidation of alkyl sulfides with chlorine can be applied (cf. F. Asinger "Chemie und Technologie der Paraffinkohlenstoffe" (1956) Berlin, pages 395, 423-424). Other methods of introduction of sulfonic acid groups, such as the sulfoxidation can be used.

The alkyl dialkanolamine corresponds to the general formula

in which R is alkyl of 2 to 5 carbon atoms, m is a number of 1 to 2 and n is 2 or 3. The alkyl dialkanolamines advantageously should be soluble in water. There may be used, for example, n - propyl - diethanolamine, isoamyl - diethanolamine, ethyl - bis - [2 - hydroxy - isopropyl] - amine, n-butyl-bis-[2-hydroxypropyl]-amine or preferably butyl

3

or isobutylamine which has been reacted with 2-2.5 moles of ethylene oxide.

As phosphoric acid esters, those derived from ortho phosphoric acid and alkanols of a medium molecular weight, containing about 4-8 carbon atoms, are preferred, for example trioctylphosphate, in particular tributylphosphate and triisobutylphosphate. These phosphoric acid esters keep their activity even when partially saponified.

The proportions by weight of the ingredients of the mixture according to the present invention are as follows:

- (a) about 10 to about 80%, preferably about 30 to about 55% of alkyl sulfonate,
- (b) about 20 to about 85%, preferably about 40 to about 65% of alkyl dialkanol amine and
- (c) about 1 to about 15%, preferably about 2 to about 6% of phosphate.

The wetting agent mixtures according to the process of the present invention are soluble in dilute as well as in highly-concentrated alkaline lyes, as they are used, for example, for mercerizing or leaching of cellulose fibres, and even in the cold.

The following examples serve to illustrate the invention but they are not intended to limit it thereto.

EXAMPLE 1

Sulfo-chlorination

120 g. of sulfur dioxide and 91 g. of chlorine are introduced at 50° C. within 10 hours into 54 g. of a straight-chain alkane of an average molecular weight of 216, obtained by a molecular sieve process and irradiated with UV-rays. After blowing out, the thickly oily sulfo chloride contains 17.9% of chlorine capable of being saponified. The yield amounts to 128 g.

Analysis: S: 15.1%, Cl: 28.3%, i.e. the product corresponds to the formula $(CH_2)_{15}(SO_2)_{2.5}Cl_{4.1}$.

Saponification

116 g. of the above-mentioned sulfo chloride are added dropwise to 158 g. of a sodium hydroxide solution of 33.4% at 50-70° C. Then the solution is stirred for 1 hour at 60-70° C., cooled and then filtered under suction from the sodium chloride which has precipitated. The clear aqueous solution then contains 46.3% of sulfonate.

Adjustment of mercerizing agents:

Solution A.—16.7 g. of isobutyl-diethanolamine and 1.4 g. of triisobutyl phosphate are added to 40 g. of the above-mentioned sulfonate solution while stirring. There are obtained 58 g. of a clear solution having a content of 61% of surface active agent.

Solution A1.—Instead of the isobutyl-diethanolamine there can also be used the same amount of a reaction product of isobutylamine with 2.3 moles of ethylene oxide which leads to the same results.

Solution B.—16.7 g. of isobutyl diethanolamine and 1.6 g. of tributylphosphate and 5.5 g. of n-butanol are added to 40 g. of a sulfonate solution obtained by the above-mentioned saponification while stirring. There are obtained 63 g. of a clear solution containing 55% of surface active agent.

A similar good wetting agent mixture is obtained when, instead of the isobutyl diethanolamine the same amount of n-butylidethanolamine is used.

Solution C.—43 g. of a commercial alkylmonosulfonate (the hydrocarbon chain having about 16 carbon atoms and containing about 77% of surface active agent) are dissolved in 53 g. of water. To this solution 37.5 g. of isobutylidethanolamine and 8 g. of triisobutylphosphate are added. The solution contains 50% of surface active agent.

The values of wetting of the following comparative test are given in Table I with the solutions A and B according to the present invention. Furthermore, the isobutylidethanolamine is also tested.

4

The determination of the wetting value is carried out in a bath containing 300 g. of sodium hydroxide according to DIN 53 901. When using 5 g. per litre of an active wetting substance the wetting times given in Table I are obtained.

TABLE I

Wetting time in sec.

Solution A	46
Solution B	60
10 Alkanopolysulfonate (Example 1)	>300
Solution C	>300
Isobutyl diethanolamine	74

The results show that the combination according to the present invention has surprisingly good wetting values.

EXAMPLE 2

230 g. of a light petrol sulfochloride which was prepared according to the Reed process by sulfo-chlorination of a light petrol (boiling at 30-80° C. and having an average molecular weight of 70) and which contains 16.9% of sulfur and 20.9% of chlorine and thus has about 6 carbon atoms per one SO_2Cl group was added dropwise within one hour at 50-60° C. into a solution of 104 g. of sodium hydroxide in 1 litre of water. After stirring for 1 hour, the reaction is complete. After filtration of some resinous impurities the solution contains 30% of sulfonate.

Preparation of the mercerizing agent solution (=solution 30 D): 70.5 g. of the above-mentioned light petrol sulfonate solution (containing 21.2 g. of sulfonate) are mixed, while stirring, with 37.5 g. of butyldiethanolamine, 26 g. of water and 8 g. of triisobutylphosphate. The clear solution then contains 42% of surface active agent.

35 This composition of mercerizing wetting agents is clearly soluble in mercerizing baths of 300 g. of sodium hydroxide/litre.

The light petrol sulfonate alone (i.e. without additions) soon creams up in these baths, i.e. it is useless.

In the following Table II the shrinkage values of the products of the present invention of Example 1 (=solutions A and B) and Example 2 (=solution D) are compared with

- 40 (1) alkanopolysulfonate of Example 1,
- (2) a mixture of commercial alkylmonosulfonate with isobutylidethanolamine (solution C).

Table II shows that, because of good solubility of the products in strong alkaline baths which product combination is obtained according to the present invention, surprisingly good shrinkage values are also obtained.

TABLE II

55 Shrinkage values measured in baths of 300 g. of sodium hydroxide/litre according to the method given in "Praktikum der Textilveredlung", Otto Meechels, page 24, (1949), Springer Verlag, Berlin-Goettingen-Heidelberg

Grams of surface active agent/litre	Shrinkage (in percent at 15° C.) after—				
	30 sec.	60 sec.	120 sec.	180 sec.	240 sec.
Solution A:					
2	3.4	7.8	11.8	13.0	13.8
3	6.8	11.8	13.8	14.4	14.6
5	9.6	12.4	13.8	14.2	14.4
Solution A1:					
2	3.6	7.5	11.6	12.8	13.2
3	7.2	12.5	13.7	14.7	13.8
5	10.0	12.7	13.8	14.8	14.5
Solution B:					
2	4.6	9.4	12.6	13.4	13.6
3	8.0	12.0	13.4	13.6	13.6
5	9.4	12.8	13.6	13.8	13.8
Solution D:					
2.5	6.0	10.8	12.8	13.0	13.2
5	8.6	11.6	12.4	13.0	13.5
Alkanopolysulfonate (according to Example 1): 5	1.6	4.2	8.4	11.2	13.2
Solution C: 5	5.4	8.6	11.4	—	12.8

5
EXAMPLE 3

Solution B was compared with an analogous solution but which contained no tributyl phosphate=solution B¹.

The wetting power was determined according to the German Industrial Standard (DIN) No. 53901 (using bakers, filled with the test liquid, in which standardized samples of cotton fabrics are inserted. The time required until sinking of the sample is a measure for the wetting power).

The foaming activity was determined as follows: 50 cc. of the test liquor was filled in a 100 cc. calibrated cylinder and shaken for 10 times. The height of the foam was determined immediately (1) and 1 minute (2) after the shaking.

The test samples indicated below contained: Sample 15 a: 6 g. of surface active agent; Sample b: 10 g. of surface active agent—each in a solution of aqueous sodium hydroxide of 27% strength.

Solution	Wetting power (seconds)		Foaming activity				20	
			Sample a		Sample b			
	Sample a	Sample b	(1)	(2)	(1)	(2)		
B	45	21	6	1	5	1	25	
B ¹	77	28	20	3	20	4		

We claim:

1. A detergent mixture consisting essentially of:
  - (a) about 10 to 80% by weight of an alkyl sulfonic acid or an alkali metal salt thereof of a straight chain hydrocarbon of 10 to 20 carbon atoms having from 1 to 3 sulfonic acid groups per molecule and pro-

30

vided on an average per one sulfonic acid group at most 7 carbon atoms are present in said molecule;

- (b) about 20 to 85% by weight of an amine of the formula

in which R is alkyl of 2 to 5 carbon atoms, n is 2 or 3 and m is a number from 1 to 2; and

- (c) about 1 to 15% by weight of a phosphoric acid triester of monohydric alkanols of 4 to 8 carbon atoms.

2. The composition as claimed in claim 1, consisting of:

- (a) about 30 to about 55% by weight of said sulfonate,
- (b) about 40 to about 65% by weight of said amine and

- (c) about 2 to about 6% by weight of said phosphate.
